Specification for Design.

Patented Oct. 18, 1921.

Application filed November 17, 1920. Serial No. 424,795. Term of patent 14 years.

To all whom it may concern:

Be it known that I, CLIFFORD G. KING, a citizen of the United States, residing at Providence, in the county of Providence and State of Rhode Island, have invented a certain new, original, and ornamental Design for an Advertising-Sign, of which the following is a specification.

In the accompanying drawing which

forms a part of this specification the figure is a perspective view of an advertising sign embodying my design.

I claim:

The ornamental design for an advertising sign, as shown.

CLIFFORD G. KING.
